[57] CLAIM

The ornamental design for a handle for plumbing fitting, as shown and described.

DESCRIPTION

FIG. 1 is a right, top, front perspective view of a handle for plumbing fitting embodying our new design;

FIG. 2 is a front elevational view thereof, the rear elevational view being identical to the front side shown;

FIG. 3 is a right side elevational view thereof, the left side elevational view being identical to the right side shown;

FIG. 4 is a top plan view thereof;

FIG. 5 is a front elevational view of a second embodiment which is essentially identical to the first embodiment but for a spacer and truncated escutcheon. The spacer has identical front and rear views;

FIG. 6 is a right side elevational view thereof, the left side elevational view being identical to the right side shown; and, FIG. 7 is a front elevational view (and a rear elevational view) of a third embodiment which is essentially identical to the second embodiment but for a decorative spacer. The spacer has identical front and rear views.

The dotted line representations of an escutcheon in FIGS. 5-7 are for purposes of illustration only and form no part of the claimed design.
